UNITED STATES PATENT OFFICE.

JOSEPH BRAUNINGER, OF TRENTON, NEW JERSEY.

GAS-STOVE AND WATER-HEATER.

1,150,333.

Specification of Letters Patent. Patented Aug. 17, 1915.

Application filed March 9, 1914. Serial No. 823,484.

To all whom it may concern:

Be it known that I, JOSEPH BRAUNINGER, a citizen of the United States, residing at Trenton, in the county of Mercer and State 5 of New Jersey, have invented certain new and useful Improvements in Gas-Stoves and Water-Heaters, of which the following is a specification.

This invention relates to gas stoves and 10 has special reference to a combined gas stove and water heater.

The principal object of the invention is to provide an improved, simplified and 15 cheap gas stove and water heater of the character described.

A second object of the invention is to provide improved means for distributing the product of combustion in such a stove.

A third object of the invention is to provide 20 improved means for heating the water chamber of such a stove.

With the above and other objects in view the invention consists in general of certain 25 novel details of construction and combination of parts hereinafter fully described, illustrated in the accompanying drawings, and specifically claimed.

In the accompanying drawings like characters of reference indicate like parts in the 30 several views, and Figure 1 is a plan view of the improved stove. Fig. 2 is a horizontal section through the stove on the line 2—2, Fig. 3, certain of the parts being shown in elevation and one of the burners being 35 partly broken away. Fig. 3 is a vertical longitudinal section through the stove on the line 3—3, Fig. 1.

In carrying out the objects of this invention there is provided an inner casing which 40 contains the combustion chambers and water heater and this inner casing is provided with the side walls 4 and the front and back walls 8. The inner casing is also provided with a top 9 upon which rests the screw 45 plugs 28 so that a removable cover 6 may be supported in spaced relation to the top. This removable cover 6 is furthermore provided with depending, outwardly flared sides 29 which hang down over the respective side, front and back walls of the inner casing in spaced relation thereto. Extending 50 between the front and back walls of the inner casing are certain partitions 8' which are arranged to provide a water space 14 and to form at each side of the water space

a pocket 10 extending downward from which through the bottom of the inner casing is an air inlet space 22.

The pockets 10 are substantially cylindrical in form and centrally disposed in 60 each pocket is a gas supply tube 12 which is provided with suitable perforations 13 on the inner side thereof. The end of this gas supply tube is squared as at 17 and is held in a suitable squared opening in the rear 65 wall 8, being retained therein by means of a pin 18. These tubes 12 are connected to a main supply tube 24 and are controlled by certain valves 25. Disposed centrally of the water space is a tubular opening 11 which 70 extends from the front to the back wall and through this opening passes the gas supply tube 15 which is likewise connected to the tube 24 and controlled by one of the valves 25. This supply tube 15 has at each side 75 thereof openings 16 and the tubular opening 11 is connected to the cylindrical pockets 10 by means of centrally disposed tubes 20. Furthermore, the tubular opening 11 has ex- 80 tending downwardly therefrom an air supply passage 22 which opens through the bottom of the inner casing. Extending upwardly from the opening 11 is a tubular flame passage 19 which opens centrally beneath the top 6 of the removable cover, so 85 that the heated products of combustion passing up therethrough may be deflected side- 90 wise and find their escape through openings 30 formed in the top 6 of said cover. Each of the chambers 10 is likewise provided with flame passages 21 which are arranged vertically above the respective tubes 12.

Extending from the water chamber at the front side of the stove are nipples 26 which constitute inlet and outlet tubes for the supply 95 of cold water and withdrawal of the heated water.

In order to facilitate the cleaning of the water chamber the said chamber has at the rear end thereof, adjacent its lower part, 100 certain clean out openings which are normally kept closed by the plugs 27.

In order to support the device in spaced relation to the floor the inner casing is held up on suitable legs 5 arranged at respective 105 corners thereof.

In operation, the gas is supplied through the respective tubes 12 and 15 and, when lit, the flame and product of combustion from the tubes 12 pass up through the openings 110

21 and strike against the top 6, passing then through the openings 30. At the same time the products of combustion from the central tube 15 pass up through the central opening 19 and in like manner pass out the openings 30, a certain portion of said flame and product passing through the tubes 20 thus heating the central part of the water chamber. Since the openings 13 are directed inward toward the water chamber the flames from these openings first strike against this chamber before passing out through the openings 21 and in like manner only the central part of the flame from the openings 16 passes through the tubes 20 the remaining portion striking the walls of the tubular chamber 11 thus also assisting in heating the water chamber.

20 The device is thus adapted to be used not only for ordinary cooking purposes but also for heating water and that without the unnecessary loss of any heat.

25 There has thus been provided a simple and efficient device of the kind described and of the character specified.

Having thus described the invention, what is claimed as new, is:—

30 1. In a stove of the class described, an inner casing having a water chamber disposed therein, a horizontally extending tubular opening formed centrally of the water chamber, a gas supply tube extending into said tubular opening, pockets at each side of said central opening, and tubes connecting said central opening and said pockets.

35 2. In a stove of the class described, an inner casing having a water chamber disposed therein, burner tubes extending through the inner casing and having openings directed toward the walls of the water chamber, and a removable cover spaced above said inner casing, said cover being provided with de-

pending sides arranged in spaced relation to said inner casing.

40 3. In a stove of the class described, an inner casing provided with a pair of laterally disposed combustion chambers and a central combustion chamber, said combustion chambers being provided with air inlets, burner tubes extending through said combustion 50 chambers, a water chamber arranged between the lateral combustion chambers and surrounding the inner combustion chamber, and means to supply and exhaust water from said water chamber.

45 4. In a stove of the class described, an inner casing comprising front, back and side walls and a centrally disposed water chamber, said water chamber being spaced from the side walls and arranged to provide lateral combustion chambers, said water chamber being further provided with a centrally disposed combustion chamber, burner tubes extending through said combustion chambers and provided with openings directed 60 toward said water chamber, passages extending from the lateral chamber to the central chamber, said chambers all being provided with air inlet passages extending upward from the bottom of said casing, a 65 flame passage extending upward from the central chamber, flame passages extending upward from the lateral combustion chambers, and a removable cover arranged in spaced relation to said inner casing and provided with escape openings for the product of combustion.

55 In testimony whereof, I affix my signature, in the presence of two witnesses.

JOSEPH BRAUNINGER.
